DECORATIVE PLASTIC PANEL FOR DOORS AND THE LIKE

Warren G. Stichtenoth, 186 Yorkwood Lane,
Cincinnati, Ohio 45238

Filed Dec. 16, 1974, Ser. No. 533,412

Term of patent 14 years

Int. Cl. D25—01

U.S. Cl. D25—62

FIG. 1

FIG. 2

FIG. 3

FIG. 1 is an isometric view of a decorative plastic panel for doors and the like embodying the decorative design of my invention;

FIG. 2 is a side elevational view as seen from all sides of FIG. 1;

FIG. 3 is a cross-sectional view along the lines 3-3 of FIG. 1.

I claim:

The ornamental design for a decorative plastic panel for doors and the like, substantially as shown and described.
